UNITED STATES PATENT OFFICE.

WILLIAM C. KEYWORTH, OF PATERSON, NEW JERSEY.

THREAD-FINISHING MACHINE.

1,119,171.

Specification of Letters Patent.

Patented Dec. 1, 1914.

Application filed February 19, 1910. Serial No. 544,834.

To all whom it may concern:

Be it known that I, WILLIAM C. KEYWORTH, a citizen of the United States, and resident of Paterson, in the county of Passaic and State of New Jersey, have invented a new and useful Improvement in Thread-Finishing Machines, of which the following is a specification.

This invention relates to thread finishing machines and in particular to the heaters thereof and to the parts intimately connected with said heaters.

One of the objects of this invention is to provide a heater which is adapted to maintain the desired degree of heat on its heating or polishing surface by the use of considerably less of the heating medium than has heretofore been necessary.

Another object is to provide a heater which is so formed and constructed as to economize the materials which necessarily enter into its construction and also to permit a plurality of heaters to be spaced more closely together than has heretofore been permissible.

A further object is to provide certain improvements in the thread guide pulley carried by the heater by which the pulley wheel of the former may be readily removed for cleaning or replacement.

A still further object is to provide certain improvements in the form, construction and arrangement of the various parts whereby the above-mentioned objects may be effectively carried out.

A practical embodiment of this invention is represented in the accompanying drawings, in which—

Figure 1 represents a side elevation of a thread finishing machine, parts intermediate the ends being broken away, Fig. 2 represents a detail elevation of one of the heaters, parts intermediate the ends being broken away, Fig. 3 represents a section taken in the plane of the line A—A of Fig. 2, looking in the direction of the arrows, Fig. 4 represents a detail horizontal section through the heater, Fig. 5 represents an enlarged detail view showing the thread guide pulley mounted on the heater, Fig. 6 represents an

enlarged side elevation of the thread guide pulley, and Fig. 7 represents a detail central section of the same.

The machine which is generally represented in Fig. 1, forms the subject matter of my Patent No. 990,564, April 25, 1911, and consequently it will not be particularly described herein. This machine includes, however, in addition to the parts to be more specifically described hereafter, thread delivery mechanisms 1, thread winding mechanisms 2, and reciprocating bars 3 for rolling the thread on the surface of the heater. Each heater is adapted to be vertically arranged in the machine and comprises an elongated hollow body portion 4, and a cap 5 therefor.

A polishing band 6 is removably secured at two places on the body portion of the heater by the screws 7, 8. This band 6 passes over the cap 5, as is well shown in Fig. 3; and a coil spring 9 is mounted in the upper end of the body portion of the heater, intermediate the body portion and the cap 5, for yieldingly holding the band 6 snugly in position on the heater.

The heater is shown in the present instance as being fitted to be heated by steam, and, to that end, there is provided a main steam inlet pipe 10 and a main steam exhaust pipe 11, the inlet pipe 10 being mounted within the exhaust pipe 11. The exhaust pipe 11 has a branch pipe 12 which is screwed into the lower end of the body portion 4 of the heater, as indicated at 13; while the inlet pipe 10 has a branch 14 which passes up through the branch 12 into the interior of the body portion 4 of the heater, and extends nearly to the top thereof.

The body portion 4 of the heater is covered on all except one side thereof, viz: the side on which the band 6 is mounted, with a non-heat-conducting jacket 15 composed of material such as asbestos fiber, and the pipes 11 and 12 are also covered in the same manner. The purpose and effect of this non-heat-conducting jacket is to prevent the outside pipes 11, 12, and the parts of the heater with which the thread being polished does not come in contact, from losing a consider-

able amount of heat through radiation; and thus a given degree of temperature may be maintained in the unjacketed side of the heater, viz: the one on which the band 6 is mounted, with a less amount of heating medium than has heretofore been required, owing to the fact that considerable heat losses have been experienced through the radiation from the steam pipes and unused portions of the heater.

10 The heater is so formed that one end of the surface on which the band 6 is mounted is wider than the other end of the said surface; in the present instance, the upper end 15 of this surface is shown as the wider one. The purpose of widening out this surface at the top is in order to provide sufficient room for the thread which is being polished to be rolled back and forth on the band 6 which 20 conforms to the shape of this surface. Inasmuch as this rolling of the thread is performed by the reciprocating rods 3 which are located at one end only of the heaters, it is not necessary to make the end of the 25 heating surface which is farthest from the rods 3 as wide as the upper end of the surfaces which are near the rod 3. It is desirable, therefore, to make the lower end of the heating surface as narrow as is feasible in 30 order to make the heater lighter, avoid the use of unnecessary material in the heater, and in particular obviate any waste of material in the band 6 for the reason that this band is commonly composed of aluminum 35 which is quite expensive.

A thread guide pulley is mounted near one end of the heater, in the present instance at the lower end of the heater, to which it is secured by a cap screw 16. This thread 40 guide pulley comprises a casing 17 which has a pair of thread retainers 18 so arranged that thread may be passed between them when it is desired to do so while preventing the thread from falling out of line with the 45 pulley wheel in case the thread may be slackened for any cause. Within this casing is a pintle 19 on which is rotatably and removably mounted a pulley wheel 20. One end of the casing 17 is open for the removal 50 of the wheel 20 when it is desired to clean or replace the same, and a cover 21 is pivotally secured to the casing 17 by the screw 22, which cover is designed to normally close the open end of the casing 17.

55 The thread in the course of being polished passes from the thread delivery mechanism 1 down in contact with the band 6 on the heater, around the pulley 20 and up again in contact with the band 6 to the thread 60 winding mechanism 2.

By the form and construction of the heater and thread guide pulley hereinabove described, there is promoted an economy of heating medium, hence an economy of fuel;

there is furthermore a considerable saving 65 in the material of which the heater itself is made and also a great saving in the aluminum or other valuable metal of which the band 6 is made. With regard to the band 6, not only does its shape show an economy 70 of material, but the fact that it does not entirely surround the heater, enables the use of about half as much aluminum as has heretofore been necessary in making a polishing band for a heater of a given size having 75 means for holding the band snugly thereon.

The arrangement of the heaters in the machine so that the thread passes up and down the front side of the heater, permits the heaters to be placed closer together than has heretofore been customary, inasmuch as 80 there is little necessity of reaching in between the heaters; the placing of the thread guide pulley on the front of the heater with the cover 21 projecting out from the machine also permits the quick cleaning and replacement of the pulley wheel 20 without the necessity of reaching in between the heaters, the construction of the pulley wheel guide 85 making the replacement very easy and rapid 90 and its location rendering it convenient.

The jacketing of the pipes and heaters with non-heat-conducting material not only promotes the economy of heating medium 95 hereinabove mentioned, but also absolutely prevents the operator from burning his or her arm when it is necessary to insert the arm in between the heaters, for instance, for the purpose of unscrewing the screw 7 to remove the polishing band.

100 It is to be understood that various changes may be resorted to in the form, construction and arrangement of the different parts of this apparatus without departing from the spirit and scope of my invention; hence I 105 do not wish to limit myself strictly to the structure herein set forth, but

What I claim is:

1. In a device of the character described, a heater provided with a side over which the 110 thread passes back and forth, non-heat conducting material applied to the remaining surface of the heater, and a polishing band secured to the heater and extending along the face over which the thread passes back 115 and forth, whereby the heat is concentrated from all other sides of the heater on to the said side and polishing band along which the thread travels.

2. In a device of the character described, 120 a heater comprising a body portion, a cap, a polishing band secured to the body in two places and passing over the cap, and yielding means interposed between the cap and body for holding the band snugly in position on the heater.

3. In a device of the character described, a heater comprising a body portion, a cap,

a polishing band removably secured to the body in two places and passing over the cap, and yielding means interposed between the cap and body for holding the band snugly
5 in position on the heater.

In testimony, that I claim the foregoing as my invention, I have signed my name in

presence of two witnesses, this sixteenth day of February 1910.

WILLIAM C. KEYWORTH.
